UNITED STATES PATENT OFFICE.

WILLIAM R. PARK, OF PHILADELPHIA, PENNSYLVANIA.

COMBINATION-TARGET.

SPECIFICATION forming part of Letters Patent No. 659,852, dated October 9, 1900.

Application filed November 27, 1899. Serial No. 738,327. (No model.)

To all whom it may concern:

Be it known that I, WILLIAM R. PARK, a citizen of the United States, residing at Philadelphia, in the county of Philadelphia and 5 State of Pennsylvania, have invented a certain new and useful Improvement in Combination-Targets, of which the following is a specification.

My invention relates to a new and useful 10 improvement in combination-targets, and has for its object to so construct such a target as to provide for the interchangeability of the face thereof and for its support either by suspension or in easel form.

15 With this end in view the invention consists in the details of construction and combination of elements hereinafter set forth and then specifically designated by the claim.

In order that those skilled in the art to 20 which this invention appertains may understand how to make and use the same, the construction and operation will now be described in detail, referring to the accompanying drawings, forming a part of this specification, in 25 which—

Figure 1 is a perspective of my improved 30 combination-target when adjusted to the form of an easel; Fig. 2, a section thereof, showing a ball caught between the pins; Fig. 3, a front view showing a different face to the target and also illustrating it as being suspended from a nail, and Fig. 4 a central section thereof.

In carrying out my invention as here embodied, A represents the board, which is preferably square, as shown, and having the holes B therein for the reception of the posts C, which when placed in position adjust the target to easel form, so that it may be supported 35 as shown in Figs. 1 and 2. The front of this board is set with a series of pins D for catching the ball, and secured or inscribed upon its face is the target E, which represents a baseball game.

40 F is a second target consisting of a disk having suitable rings and designations thereon and the holes G therein, said holes per-

mitting the placing of the target-disk over the pins D, as will be readily understood.

H represents pegs, preferably of wood, 50 which are adapted to pass through suitable holes formed in the targets and into the holes I in the target-board, and thus serve to hold the targets in place. By this arrangement any number of targets may be utilized and all 55 may be kept upon the target-board, the outer one being used in the game being played, and when another game is to be played the outer one may be removed, exposing the next one below.

60 Of course I do not wish to be limited to the particular shape nor to the material of which the target-disks are made, as this is immaterial.

When the target is not to be used in the 65 form of an easel, the posts C are withdrawn from the board, and the latter may then be suspended upon a suitable peg or nail J by means of the hole K; but it is often inconvenient to hang a target upon a wall, and therefore the adjustment for use as an easel is 70 specially advantageous, since the target may then be placed upon the floor and serves the purpose admirably.

Having thus fully described my invention, 75 what I claim as new and useful is—

In combination, a target comprising a board suitably shaped and supported having holes therein, a series of pins set in the front of the board and having heads on their free ends, 80 disks suitably stamped or printed having holes, said disks being adapted to pass over the pins of the board, and pegs adapted to pass through the disk and be inserted in certain of the holes in the board, said pegs having 85 knobs on their free ends adapted to bear against and rigidly hold the disks in place.

In testimony whereof I have hereunto affixed my signature in the presence of two subscribing witnesses.

WILLIAM R. PARK.

Witnesses:

MARY E. HAMER,
S. S. WILLIAMSON.
